US0D1089217S

(12) **United States Design Patent** (10) Patent No.: **US D1,089,217 S**
(45) Date of Patent: ** Aug. 19, 2025

(54) **COMPUTER STAND**

(71) Applicant: **Dawei Yao**, Dongguan (CN)
(72) Inventor: **Dawei Yao**, Dongguan (CN)
(**) Term: **15 Years**
(21) Appl. No.: **29/923,698**
(22) Filed: **Dec. 31, 2023**
(51) LOC (15) Cl. **14-06**
(52) U.S. Cl.
USPC **D14/451**

(58) **Field of Classification Search**
